UNITED STATES PATENT OFFICE

LOUISE PESZYNSKA, OF PARIS, FRANCE

DESIGN FOR A BOTTLE

Application filed June 28, 1929. Serial No. 31,865. Term of patent 7 years.

To all whom it may concern:

Be it known that I, LOUISE PESZYNSKA, a citizen of the Republic of France, residing in the city of Paris, France, have invented a new, original, and ornamental Design for Bottle, of which the following is a specification, reference being had to the accompanying drawing, forming a part thereof.

In the drawing

Fig. 1 is a perspective view of my bottle,
Fig. 2 is a side view, and
Fig. 3 is a top view thereof.
The line "A" indicates the line of demarcation between stopper and bottle.

I claim:

The ornamental design for a bottle as shown and described.

LOUISE PESZYNSKA.
